UNITED STATES PATENT OFFICE.

WILHELM KOLMER AND ERHARD WIRSCHINGER, OF AUGSBURG, GERMANY, AS-
SIGNORS TO MASCHINENFABRIK AUGSBURG-NUERNBERG, AKTIENGESELLSCHAFT,
OF AUGSBURG, GERMANY, A CORPORATION OF GERMANY.

TWO-REVOLUTION FAST PRINTING PRESS.

Application filed April 22, 1926, Serial No. 103,815, and in Germany May 9, 1925.

In the well known two-revolution fast printing presses, the ink trough together with the ductor roll and vibrator is arranged near the front edge of the machine below the delivery table, so that the operator who stands in front of the machine can see the printed sheets as they are delivered to the delivery table and can regulate the operation of the inking apparatus. In this type of machine, the ink is taken off the vibrator by a reciprocating table which serves at the same time as the ink distributing table, and whereby the ink is transferred to the inking device proper. The distributing rollers are, in this type of machine, also arranged below the delivery table. Such a machine permits only a comparatively low small pile of sheets to be worked with, which necessitates frequent changing of the sheet pile, causing much loss of time now the present object of the invention is to obviate this defect.

According to this invention, the inking apparatus which is designed as a cylinder inking apparatus, is arranged between the impression cylinder and the delivery table for the printed sheets. The ink is transferred to the inking device in well known manner by means of an ink table which receives a band of ink from a vibrator located near the front edge of the machine, and transferring the ink to a vibrator of the cylinder inking device. The first named vibrator which picks up the ink from the ductor roll, is placed at such a low level that the apex of the vibrator in its upper position does not lie above or lies only very slightly above the top surface of the letterpress or other printing surface. This arrangement enables the entire space between the upper surface of the letterpress or other printing surface and the delivery device to be utilized for the vertically adjustable delivery pile table. The pile of delivered printed sheets may therefore be much higher than in the old machines, so that it need not be so frequently removed.

The drawing shows diagrammatically by way of example one embodiment of the invention in elevation.

The printed sheets are discharged in well-known manner from the impression cylinder *a* by means of the delivery tapes *b* and are delivered to the table *c* which is vertically

adjustable. The inking device proper *d* is arranged between the impression cylinder *a* and the delivery table *c*. The ink trough *e* provided with the ductor roll *f* is arranged near the front edge of the machine. The vibrator *g* which takes a band of ink off the ductor roll *f*, is arranged so low that its apex, in the upper position of the roll does not project above the surface of the letterpress or other printing surface *h*. The ink is taken from the vibrator *g* by a reciprocating table *i* and is thereby transferred to a second vibrator *k* which in turn transfers the ink to the distributing rollers of the cylinder inking device. The vibrator *k* is arranged to move downwards to pick up the latter from the ink table *i* whilst the ink travels under the vibrator toward the impression cylinder *a*. During the remainder of the operation the vibrator *k* remains above the letterpress or other printing surface *h* and participates in the distribution of the ink. The ink is transferred by the vibrator *k* to the distributing rollers *l* and by these rollers to the inking rollers *d*. Additional ink distributing rolls *m* may be provided upon the ink table *i* in the well known manner. These additional rolls *m* must, of course, also be arranged so low that their apices lie below the surface of the letterpress or other printing surface *h*. As shown in the drawing, the vibrator *K* is carried by a lever *n* adapted to be rocked about the axis of roller *l*, by means of the pivoted links *o* and *p*, by the two-arm lever *r*, pivoted at *q* and actuated by the cam *s*. The latter is mounted on a rotatable shaft driven in any convenient manner.

What we claim is:

1. In a two-revolution fast printing press, the combination with the impression cylinder, the delivery table and the ink distributing device interposed between said impression cylinder and delivery table, of an ink trough located at the front of the machine, a vibrator adapted to receive ink from said ink trough and located in a horizontal plane below the printing surface, and a reciprocating table adapted to cooperate with said vibrator and to transfer the ink therefrom to said ink distributing device.

2. The combination as specified in claim 1 comprising a second vibrator, and means for periodically rocking said second vibra-

tor into contact with said reciprocating table.
3. The combination as specified in claim
1 comprising a second vibrator, said second
vibrator forming a part of said ink dis-
tributing device and adapted to rock about
the axis of one of the distributing rollers,
and means for periodically rocking said sec-

ond vibrator into contact with said recip-
rocating table.

In testimony whereof we have affixed our 10
signatures.

WILHELM KOLMER.
ERHARD WIRSCHINGER.
